(57) **CLAIM**

We claim the ornamental design for a cassette for bioaerosol sensor, as shown and described.

DESCRIPTION

FIG. 1 is a perspective view of a cassette for bioaerosol sensor showing our new design from the top, front, and right side;

FIG. 2 is another perspective view thereof shown from the bottom, rear, and left side;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is another perspective view thereof shown from the top, front, and right side in an exploded configuration;

FIG. 10 is another perspective view thereof shown from the bottom, rear, and left side in an exploded configuration;

FIG. 11 is a top plan view thereof in an exploded configuration;

FIG. 12 is a bottom plan view thereof in an exploded configuration;

FIG. 13 is a front elevation view thereof in an exploded configuration;

FIG. 14 is a rear elevation view thereof in an exploded configuration;

FIG. 15 is a right side elevation view thereof in an exploded configuration; and,

FIG. 16 is a left side elevation view thereof in an exploded configuration.

The broken lines adjacent to the shaded areas depict boundaries of the claim and form no part of the claimed design. The dash-dot-dash broken lines depict boundaries of the claim and form no part of the claimed design. All other broken lines illustrate unclaimed portions of the cassette for bioaerosol sensor and form no part of the claimed design.
